UNITED STATES PATENT OFFICE.

MAX SCHWENDNER, OF READING, PENNSYLVANIA, ASSIGNOR TO THE
READING HARDWARE COMPANY, OF SAME PLACE.

DESIGN FOR AN ESCUTCHEON-PLATE

SPECIFICATION forming part of Design No. 22,025, dated November 29, 1892.

Application filed October 11, 1892. Serial No. 448,582. Term of patent 7 years.

To all whom it may concern:

Be it known that I, MAX SCHWENDNER, a citizen of Germany, residing at Reading, in the county of Berks, State of Pennsylvania, 5 have invented a certain new and original Design for an Escutcheon-Plate, of which the following is a specification.

The main features of my design shown in the accompanying drawing are the representation of the ribbon-bound bar with the depressed shelf or ledge upon which said bar rests, and the ornamental molding extending beyond the ledge.

Referring to the drawing, which represents 15 my design for an escutcheon-plate, *a* represents a ledge or shelf which extends around and is depressed below the inclosed portion *b* of the plate. Upon this depressed ledge ap-

pears the ornamental bar *c*, represented as wound with a ribbon extending in a continuous piece around the bar, the coils of the ribbon bearing upon the surface of the ledge and the adjacent wall of the raised central portion of the plate. The portion *d* of the border lying beyond the ledge is concaved 25 and ornamented, as shown.

What I claim is—

The design for an escutcheon-plate or similar article of builders' hardware, substantially as shown. 25

In testimony whereof I affix my signature in presence of two witnesses.

MAX SCHWENDNER.

Witnesses:

GEO. E. TYSON,
W. MANNERBACK.
